Primary Examiner — Jack Reickel*Assistant Examiner* — John M Otte(74) *Attorney, Agent, or Firm* — RatnerPrestia(57) **CLAIM**

The ornamental design for a circulator cooker display, as shown and described.

DESCRIPTION

FIG. 1 is a top plan view of a circulator cooker display showing our new design; and,

FIG. 2 is an isometric view thereof, shown applied to an exemplary circulator cooker.

The circulator cooker display is a flat surface on a circulator cooker body. The circulator cooker body is represented by dash-dot-dash lines in FIG. 1. The broken lines in the drawings are for the purpose of illustrating unclaimed portions of the circulator cooker design and form no part of the claimed design.
